(57) **CLAIM**

The ornamental design for a bee feeder mason jar lid as shown and described.

DESCRIPTION

FIG. 1 is a top view of a bee feeder mason jar lid showing my new design;

FIG. 2 is a perspective view thereof;

FIG. 3 is a side view thereof;

FIG. 4 is a perspective view thereof;

FIG. 5 is a perspective view thereof;

FIG. 6 is a perspective view thereof; and,

FIG. 7 is an environmental side view thereof.

The broken lines depict environment or unclaimed features of the bee feeder mason jar lid, for illustrative purposes only and form no part of the claim.

The bee feeder mason jar lid has a two-tiered profile smooth bottom portion and a ridged lower portion opposite a threaded interior, and a top view that has a ring of openings along the periphery opposite the smooth portion.
